CIGARETTE DISPENSER

Robert M. Frederick, Richland, Wash.

Application May 23, 1950, Serial No. 163,611

1 Claim. (Cl. 312—80)

1

This invention comprises novel and useful improvements in a cigarette dispenser, and more specifically pertains to an improved automatic storage and dispensing device for cigarettes and the like.

The primary object of this invention is to provide an improved construction of a combined storage and dispensing device, and one wherein the dispensing mechanism shall have an improved and extremely efficient mechanism for automatically removing a single cigarette or the like from a storage magazine and dispensing the same.

A further object of the invention is to provide a mechanism in conformity with the preceding objects which shall be capable of convenient and compact mounting in various attractive types of cabinets and the like.

A further object of the invention is to provide an apparatus in conformity with the foregoing objects in which a dispensing tray shall remove a single cigarette from a storage magazine while positively preventing egress of other cigarettes stored therein; shall withdraw the selected cigarette to a predetermined position, and shall automatically lift or eject the cigarette from the tray into a position for easy removal of the same.

Yet another object of the invention is to provide an apparatus in conformity with the foregoing objects which shall consist of a minimum of moving parts, shall be entirely dependable and automatic in its operation, and shall be of inexpensive and light-weight construction.

These, together with various ancillary features and objects of the invention which will later become apparent as the following description proceeds, are attained by the present invention, preferred embodiments of which have been illustrated, by way of example only, in the accompanying drawings, wherein:

Figure 1 is a perspective view of one embodiment of apparatus incorporating therein the principles of this invention and specifically adapted for use in automobiles, cars or other vehicles and similar environments;

Figure 2 is a perspective view of a second embodiment of the invention, specifically adapted for use in the rooms of houses and the like;

Figure 3 is a vertical longitudinal sectional view taken substantially upon the plane indicated by the section line 3—3 of Figure 1, and showing the interior construction of the embodiment of Figure 1, the parts being shown in the closed position of the dispensing tray;

Figure 4 is a view similar to Figure 3 but show-

2

ing the position of the parts when the tray is in its open or dispensing position;

Figure 5 is a vertical longitudinal sectional view through the embodiment of Figure 2, showing the dispensing tray in its closed position, this view being taken substantially upon the plane indicated by the section line 5—5 of Figure 6; and

Figure 6 is a vertical transverse sectional view taken substantially upon the plane indicated by the section line 6—6 of Figure 5.

Referring now more specifically to the accompanying drawings, wherein like numerals designate similar parts throughout the various views, it will be here observed that the novel construction and mechanism for withdrawing a single cigarette from a storage magazine, removing this cigarette from the cabinet; and automatically elevating or rejecting the cigarette from the withdrawing means constitutes an essential feature of this invention and may be embodied in a variety of cabinets of different types, specifically adapted for specialized uses, two of these uses or arrangements being shown in Figures 1 and 2.

Referring first to the arrangement of Figure 1, it will be seen that there is disclosed a cabinet indicated generally by the numeral 10 and which may be of any desired construction, size, shape, material and appearance, it being only essential that the same shall contain therein an upper chamber constituting a magazine or storage chamber 12 for receiving cigarettes or similar articles, and a lower chamber 14 in which is movably received the actuating mechanism of the automatic dispenser. Preferably, the cabinet 10 will be of an attractive and even ornamental appearance, and will be constructed of inexpensive and light-weight materials, such as plastic or sheet metal, having the requisite strength.

In the embodiment illustrated in Figures 1, 3 and 4, the cabinet 10 includes a pair of side walls 16, a back wall 18, a bottom wall 20, these walls being conveniently of an integral or a rigidly assembled construction.

In suitable horizontally disposed grooves or channels 22 formed in the upper adjacent surfaces of the side walls 16 is slidably received a panel 24 constituting a support for or the base of an ash tray or the like, indicated generally at 26. By this means, the ash tray may be slidably removed from the cabinet when it is desired to empty, cleanse or service the same or to charge the magazine or reservoir 12, and may be effectively retained upon the cabinet when the side

edges of the plate 24 are received in the channels 22.

The bottom of the magazine 12 is constituted by an inclined bottom wall 28, which extends and is connected to the two side walls 16 and to the back wall 18, the bottom wall sloping downwardly and forwardly toward the front of the cabinet, but terminating short thereof to provide a discharge opening therebetween.

The upper portion of the front of the cabinet is closed, as by a panel 30 which may be integral with or may be separately attached to the walls of the cabinet, leaving an opening 32 below the panel 30. Upon the adjacent surfaces of the side walls 16 there are provided laterally extending ribs 34 constituting supports or guides upon which is slidably mounted a panel 36 of any desired material and referred to hereinafter as a tray. This tray 36 is provided with a panel 38 at its front extremity which is adapted to enclose or cover the opening 32 in the front of the cabinet. A knob or the like 40 may be applied to the closure panel 38 to facilitate movement of the tray. The tray can be slid into the cabinet, as shown in Figure 3, or may be slid outwardly therefrom as shown in Figure 4. In either position, however, the upper surface of the tray slidably engages the under surface of the bottom wall 28 of the magazine 12 to at all times close the discharge opening thereof except when an appropriately positioned slot 42 extending vertically through the tray 36 is in registry with this discharge opening. It is of course possible that a recess in the upper surface of the tray 36 might be substituted for the slot 42, it being merely essential that there is provided a space which is of a sufficient size to receive therein a single cigarette or other article 44 stored in the magazine 12 whereby, when the tray is withdrawn, the cigarette 44 recessed therein will be withdrawn therewith.

It will be seen that as so far described when the tray is pushed into its closed position as shown in Figure 3 a cigarette, under the influence of gravity, will drop from the magazine 12 through the discharge opening and into the recess 42 of the tray, whereby, when the tray is moved to its open position as shown in Figure 4, this cigarette may be withdrawn from the recess or slot 42, the discharge opening being closed the moment the recess 42 is out of registry with the same to prevent removal of any other cigarette than that which is received and recessed within the opening 42.

However, the principles of this invention further include not only the above described tray construction for withdrawing a single cigarette from a storage magazine, but also comprise means for automatically ejecting or elevating the cigarettes so withdrawn into a position for convenient removal by the user. This automatic ejecting mechanism may obviously be of various constructions, that illustrated in the drawings being deemed to be highly satisfactory for purposes of this invention.

Secured to either one or a pair of depending supporting standards 46 attached to the under surface of the tray 36 and within the chamber 14, as by a pivot pin 48, is a lever 50 which has its center of gravity forwardly of the pivot pin 48 whereby the lever is normally gravity-urged into what may be termed its lowered position. This lowered position of the lever is limited by the engagement of a cam or stop surface 52 appropriately shaped and formed upon the rear portion of the lever, this stop surface being adapted to

engage the under surface of the tray 36 and to limit further counter-clockwise rotation of the lever with respect to the tray. At its other end, the lever is provided with an upstanding arm 54 which has a cylindrical member 56 thereon constituting a cradle for supporting and receiving one of the cigarettes 44. The arm 54 and cradle 56 are so disposed that when the lever is in its lowered position, as shown in Figure 3, the cradle will be disposed just above the lower edge of the slot 42 to constitute a bottom for the same and support a cigarette 44 therein, as shown in Figure 3. However, when the lever is rotated in a clockwise direction, as shown in Figure 4, the arm 54 and cradle 56 will be raised, thus elevating the cigarette resting upon the cradle into an elevated position, whereby the same may be readily and accessibly removed by the user.

In order to effect this clockwise rotation of the lever, a cam arrangement is provided consisting of an appropriately curved lower camming surface 58 formed on the front portion of the lever, which is adapted to engage with a fixed surface 60 formed by the bottom edge of the slot or opening 32 of the front of the cabinet. It will now be seen that by appropriately contouring the cam surface 58 that upon opening of the tray 36 to the position shown in Figure 4, the cam surface 58 will slide upon the fixed surface 60 and thus cause the raising or clockwise movement of the lever to effect elevating of the cradle and its cigarette. Obviously, upon moving the tray to its closed position, the camming surface will be disengaged and under the influence of gravity the lever will drop back to its original position, and when the slot 42 registers with the discharge opening, another cigarette will, under the influence of gravity, drop into the slot 42 and rest upon the cradle 56.

Obviously, the cabinet 10 can be supported in various ways, and can even be employed by resting upon its base 20. However, there has been illustrated a conventional form of suction cup 60 detachably secured to the back wall 18 as by a fastening screw 62, whereby the cabinet may be removably mounted upon vertical surfaces such as the windshield, window glass or various panels within a motor vehicle, or in various other environments.

Referring now to the embodiment illustrated in Figures 2, 5, and 6, it will be seen that there is disclosed a similar construction of cabinet, indicated generally by the numeral 70, this cabinet having side walls 72, a back wall 74 having ends 76 and 78 which extend respectively above and below the top and bottom of the cabinet 70 and are provided with apertures 80 by means of which the cabinet may be mounted or supported. The cabinet is further provided with a bottom wall 82, a top wall 84, and with a front panel 86 preferably integrally formed with the top wall 84. It is contemplated that the side walls and bottom wall shall be of integral construction, as shown in Figure 6, with the back wall 72 being removable, and with an integral partition 88 formed in the interior of the cabinet and dividing the same into an ash tray compartment 90 formed in the lower portion of the cabinet and a space above the same. Slidably received in the ash tray compartment 90 is a conventional form of ash tray 92 of any desired character, the same having integrally attached thereto a front wall 94 which also constitutes a closure panel having a closure handle 96, for the front of the cabinet. Supported upon integral ribs or rails 98 which are

positioned upon the adjacent surfaces of the side walls 72 and midway between the partition 88 and the top panel 84 is a slidable panel 100 constituting a tray and which is provided with a panel 102 at its front end having a knob 104 and constituting a further closure for the open front of the cabinet. As in the preceding embodiment, this tray is provided with a recess or slot 106, and carries depending support brackets 108 upon which is pivoted, as at 110, a lever 112 having a camming surface 114, a curved stop surface 116, a support arm 118 and a cigarette receiving cradle 120, all as disclosed in the preceding embodiment. The tray divides the upper portion of the cabinet into two compartments, that indicated at 122 constituting a magazine having a bottom wall 124 of identically the same construction as that set forth in connection with the previous embodiment, and a lower compartment 126 which receives the tray and the ejecting mechanism.

The operation of this form of the invention is identical with that previously set forth except for the slightly different construction of the cover for the magazine and the provision of a slideable ash tray within the base of the cabinet.

It is to be understood that the novel tray, and the automatic ejecting mechanism may obviously be used with various types of cabinets and in different constructions as desired, the two cabinets illustrated being intended as illustrative rather than restrictive of the principles of the invention.

Since, from the foregoing, the construction and advantages of this cigarette dispenser are readily apparent, further description is believed to be unnecessary.

However, since numerous modifications and equivalents will readily occur to those skilled in the art after a consideration of the foregoing specification and accompanying drawings, it is not intended to limit the invention to the exact embodiment shown and described, but all suitable modifications and equivalents may be re-

sorted to which fall within the scope of the appended claim.

Having described the invention, what is claimed as new is:

- 5 A cigarette dispenser comprising a cabinet having a magazine for cigarettes, said magazine having a sloping bottom wall with a discharge opening, said cabinet having a front wall with an aperture therein, a horizontally disposed integral flat, plate-like cigarette delivery tray slidably mounted in said cabinet below said bottom wall and slideable through the upper portion of said aperture, said tray having a vertical slot extending entirely therethrough and registerable with said discharge opening for receiving a single cigarette, a lever disposed beneath said tray and mounted thereon for vertically pivoting movement, a cigarette support member on said lever receivable and vertically movable through said 10 vertical slot, an actuating cam on the bottom surface of said lever engageable with the lower edge of said aperture in the open position of the tray for imparting upward pivoting movement to the lever and effecting upward movement of the support member through the vertical slot, an abutment surface on said lever engageable with the bottom surface of the tray to limit downward movement of the lever and halt downward travel of the support member within the bottom portion 15 of the vertical slot.
